ELECTRIC CIRCUIT BREAKER

Leonide P. Koval, Far Rockaway, N.Y., assignor to General Electric Company, a corporation of New York

Filed July 17, 1962, Ser. No. 210,375

4 Claims. (Cl. 200—116)

My invention relates to electric circuit breakers, and particularly to electric circuit breakers of the type including a contact arm operated by a pair of toggle links, the toggle links being supported on a releasable support or "cradle."

In circuit breakers of the type described, it has been found that when the parts are constructed and arranged to provide maximum contact pressure in the closed position, it is necessary to provide means for maintaining the toggle links in at least a partially collapsed condition when tripping occurs. This is necessary to provide a desired bias force to move the breaker handle to "trip-indicating" position, and also to move the movable contact to a maximum open position.

In accordance with the prior art, such means has been provided comprising a portion of the toggle-support or "cradle" member, adapted to engage the toggle links upon tripping, to maintain the toggle links in partially collapsed condition.

Such construction requires that the releasable support and the toggle links be so constructed and arranged that the desired inter-action can take place. Such construction and arrangement, however, may not be desirable from the point of ease of assembly, and avoidance of highly concentrated forces.

It is an object of the present invention to provide an electric circuit breaker having an operating mechanism of the type described including means for maintaining the operating toggles in partially collapsed condition upon tripping without the necessity of inter-action between the releasable support members and the toggle.

It is another object of the invention to provide an electric circuit breaker having an operating mechanism of the type described including means for maintaining the operating toggles in partially collapsed condition upon tripping, which does not require the use of additional movable parts in the mechanism.

In accordance with the invention in one form, a circuit breaker operating mechanism is provided including a support and at least one contact arm pivotally supported on the support. For operating the contact arm, a pair of toggle links are provided. One end of the toggle linkage is pivotally supported on the contact arm. The other end of the toggle linkage is pivotally supported on a releasable support or "cradle," which is pivotally supported on the support at one end and releasably latched with respect to the support at the other end. An operating spring is provided, having one end connected to the knee of the toggle linkage and the other end carried by an arcuately movable handle member.

In accordance with the invention, the toggle link connected to the contact arm is provided with an extension which, in the tripped condition, engages a rigidly mounted stop which limits movement of the lower toggle link toward straightened condition.

The invention will be more fully understood from the following detailed description, taken in conjunction with the accompanying drawings, and its scope will be pointed out in the appended claims.

FIGURE 1 is a side elevation view of an electric circuit breaker incorporating the invention, portions of the casing being broken away, the parts being shown in the "OFF" condition;

FIGURE 2 is a side elevation view of the mechanism

2

of FIGURE 1, the parts being shown in the "ON" condition;

FIGURE 3 is a side elevation view of the mechanism of FIGURE 1, the parts being shown in the "TRIPPED" condition;

FIGURE 4 is an end elevation view of a portion of the circuit breaker mechanism, taken generally on the line 4—4 of FIGURE 3, and

FIGURE 5 is an exploded perspective view of a portion of the mechanism of the circuit breaker of FIGURE 1.

Referring to FIGURE 1, the invention is shown as incorporated in an electric circuit breaker comprising an insulating casing including a base 2 and a cover 3. The casing 1 is generally rectangular and includes three line terminals (not shown) at one end, and three load terminals (not shown) at the other end. Electrical continuity between each pair of corresponding line and load terminals is adapted to be controlled by a pair of contacts including a relatively movable contact 4 and a stationary contact 5 (only one pair shown).

Each of the movable contacts 4 is carried by a movable contact support 6, which is pivotally connected to a contact arm 7 by pivot pin 14. The forward end of the contact support 6 has a post 6A extending through the contact arm 7. A compression spring 6A' is positioned on post 6A between the support 6 and the arm 7, and a cotter pin 6B limits movement of the support 6 away from arm 7. The contact support 6 has a flexible connector 6C connected thereto adjacent the pivot pin 14 by suitable means such as by brazing. The contact arm 7 for the center pair of line and load terminals, as illustrated in FIGURE 1, is pivotally supported on pin 8 carried by side plate portions of a stationary frame assembly 9.

The contact arm 7 for each pair of line and load terminals is anchored by suitable fastening means 10, to a contact cross-arm 11 of reinforced insulating material. Thus movement of the center contact arm 7 carries with it the two outside contact arms.

For the purpose of operating the center contact arm 7 between open and closed circuit positions, operating mechanisms is provided including a toggle linkage comprising a side-by-side pair of upper toggle links 12, and a pair of lower toggle links 13. The lower toggle links 13 comprise portions of a single-bifurcated member, as shown particularly in FIGURE 4, and are pivotally connected to oppose depending side portions of the contact arm 7 by the pivot pin 14.

The upper toggle links 12 are connected to the lower toggle links 13 by knee pivot pin 15. The upper toggle links 12 are also connected by pivot pin 16 to a releasable support or "cradle" member 17.

The cradle member 17 is pivotally supported at one end of the support frame 9 by pivot pin 18. The cradle member 17 is releasably latched at its other end by a suitable latch member 19. The latch member 19 is adapted to be moved or permitted to move to releasing position by suitable current-responsive means, not shown.

The toggle linkage comprising links 12 and 13 is adapted to be operated between collapsed and straightened conditions by means of a manually operable handle member 20, carried by a handle support member 21.

The handle support member 21 is generally bifurcated or U-shaped, and is pivotally supported on the sides of the frame member 9 on pivot supports, not shown.

Movement of the handle member 20 from the position shown in FIGURE 1 to the position shown in FIGURE 2 moves the operating spring 22 which is connected between the handle support member 21 and the knee pivot pin 15 of the toggle linkage, across the line of centers of pivot pins 15 and 16, and moves the toggle linkage from

collapsed position as in FIGURE 1 to straightened position as in FIGURE 2 with a snap action. This also moves the movable contacts 4 to closed circuit position as shown in FIGURE 2.

Upon the occurrence of predetermined current conditions through the contacts 4 and 5, the member 17 is released from the latch 19 and the parts thereupon move to the position shown in FIGURE 3.

For the purpose of maintaining the toggle links in a more collapsed position than they would otherwise assume when tripping occurs, the lower toggle links 13 are each made generally L-shaped, having an extension 13'. The frame member 9 is provided with a pair of rigidly mounted stops or pins 24, each extending inwardly from one side of the frame 9. The stop pins 24 are further supported by means of auxiliary support members 24A as shown particularly in FIGURES 4 and 5. Each piece 24A includes a bent-over portion 24B which fits over the lower edge of the frame-side 9. This, together with hole 24C, which fits over the end of pin 8, retains the piece 24A in position. The pin 24 extends through the hole 24D as well as through an aligned hole in the side of the frame 9. On release of the cradle 17, the parts move from the position shown in FIGURE 2 to the position shown in FIGURE 3. It will be observed that the toggle links, including the pins 14 and 16, move generally upwardly at this time. As this occurs, the extensions 13' of the toggle links 13 engage the stop members 24 carried by the frame 9, and cause the links 13 to rotate slightly clockwise about their pivot 14.

This maintains the knee 15 of the toggle linkage in a position offset slightly to the right as viewed, and has the dual effect of causing the operating spring 22 to exert more of a bias on the handle 20, tending to move it to mid- or trip-indicating position, and of moving the contact arm to fully open position, in which it engages the member 27, surrounding the pivot pin 18, as a stop.

In order to reset the mechanism, the handle 20 is moved clockwise as viewed, causing the handle support member 21 to engage the cradle 17, rotating it clockwise until the portion 17' re-engages the latch member 19. The mechanism is then re-set and can be reclosed by moving the handle in counterclockwise direction.

The depending side portions of the channel-shaped contact arm 7 are provided with cut-away recesses or notches 7' to afford clearance for the stop pins 24.

It will be observed from FIGURE 4 that the ends 13' of the lower toggle link engage the pins 24 at a portion spaced from the inner surface of the frame 9, due to the fact that clearance must be afforded for the sides of the channel-shaped contact arm 7.

Also, it will be observed that the pins 24 cannot be made unitary, i.e., part of a single pin going between the sides of frame 9 due to the fact that space must be left for the flexible conductor 6C (see FIGURE 4). Thus there is a tendency for the pins 24 to be tilted from their supported ends under the impact of ends 13' when tripping occurs. The reinforcing pieces 24A support the pins 24 at the opposite side of the frame 9 and prevent such tilting.

While the invention has been shown in one particular embodiment, it will be readily appreciated that many modifications thereof may be made, and I therefore intend, by the appended claims, to cover all such modifications as fall within the true spirit and scope of the invention.

What I claim as new and desire to secure by Letters Patent of the United States is:

1. An electric circuit breaker comprising:

- (a) a support,
- (b) at least one movable contact arm pivotally supported on said support,
- (c) operating means for operating said movable contact arm between open and closed circuit positions, said operating means comprising a releasable toggle-

supporting member pivotally supported on said support,

- (d) upper toggle links pivotally connected to said releasable support at one end,
- (e) a pair of lower toggle links pivotally connected to said movable contact arm at one end,
- (f) a knee pin interconnecting said upper and lower toggle links,
- (g) a handle member pivotally supported on said support,
- (h) an operating spring having one end connected to said handle member and its other end connected to said knee pin of said toggle linkage,
- (i) latch means normally restraining said releasable toggle-supporting member in latched position and operable in response to predetermined current conditions to release said releasable toggle-supporting member,
- (j) stop means rigidly attached to said support and spaced from said pivotal connection of said toggle links to said contact arm, and
- (k) said lower toggle links including means engaging said stop means following release of said releasable means and maintaining said toggle linkage in a partially collapsed position following release of said releasable means.

2. An electric circuit breaker comprising:

- (a) a support,
- (b) at least one movable contact arm pivotally supported on said support,
- (c) operating means for operating said movable contact arm between open and closed circuit positions, said operating means comprising a releasable toggle-supporting member pivotally supported on said support,
- (d) upper toggle links pivotally connected to said releasable support at one end,
- (e) a pair of lower toggle links pivotally connected to said movable contact arm at one end,
- (f) a knee pin interconnecting said upper and lower toggle links,
- (g) a handle member pivotally supported on said support,
- (h) an operating spring having one end connected to said handle member and its other end connected to said knee pin of said toggle linkage,
- (i) latch means normally restraining said releasable toggle-supporting member in latched position and operable in response to predetermined current conditions to release said releasable toggle-supporting member,
- (j) stop means rigidly attached to said support between said pivot of said contact arm on said support and said pivotal connection of said toggle links and said contact arm, and
- (k) said lower toggle links including means engaging said stop means following release of said releasable means and maintaining said toggle linkage in a partially collapsed position following release of said releasable means.

3. An electric circuit breaker comprising:

- (a) a support,
- (b) at least one movable contact arm pivotally supported on said support,
- (c) operating means for operating said movable contact arm between open and closed circuit positions, said operating means comprising a releasable toggle-supporting member pivotally supported on said support,
- (d) upper toggle links pivotally connected to said releasable support at one end,
- (e) a pair of lower toggle links pivotally connected to said movable contact arm at one end,
- (f) a knee pin interconnecting said upper and lower toggle links,

- (g) a handle member pivotally supported on said support,
  - (h) an operating spring having one end connected to said handle member and its other end connected to said knee pin of said toggle linkage,
  - (i) latch means normally restraining said releasable toggle-supporting member in latched position and operable in response to predetermined current conditions to release said releasable toggle-supporting member,
  - (j) said toggle links including a first toggle link connected to said contact arm, said first toggle link including an offset portion extending generally at right angles to the remaining portion, and
  - (k) stop means rigidly attached to said support between said pivot of said contact arm on said support and said pivotal connection of said toggle links and said contact arm, and
  - (m) said offset portion of said toggle links being engageable with said stop means following release of said releasable means to maintain said toggle linkage in a partially collapsed position.
4. An electric circuit breaker comprising:
- (a) a support,
  - (b) at least one movable contact arm pivotally supported at a first point thereof on said support,
  - (c) operating means for operating said movable contact arm between open and closed circuit positions, said operating means comprising a releasable toggle supporting member pivotally supported on said support,
  - (d) at least one upper toggle link pivotally connected to said releasable support at one end,

5

10

20

- (e) at least one lower toggle link pivotally connected to said movable contact arm at a second point on said contact arm spaced from said first point,
- (f) a knee pin interconnecting said upper and lower toggle links,
- (g) a handle member pivotally supported on said support,
- (h) an operating spring having one end connected to said handle member and having its other end connected to said knee pin of said toggle links,
- (i) latch means normally restraining said releasable toggle supporting member in latched position and operable in response to predetermined current conditions to release said releasable toggle supporting member,
- (j) said lower toggle link including a portion extending generally at right angles to the remaining portion from said second point generally toward said first point,
- (k) stop means fixedly carried by said support adjacent said first point of said contact arm,
- (m) said right angles extending portion of said lower toggle link engaging said stop means and maintaining said toggle in a partially collapsed position following release of said releasable means.
